UNITED STATES PATENT OFFICE.

MAX M. MUELLER, OF CHICAGO, ILLINOIS.

LABELING-MACHINE.

1,121,390.

Specification of Letters Patent. Patented Dec. 15, 1914.

Application filed April 3, 1914. Serial No. 829,253.

To all whom it may concern:

Be it known that I, MAX M. MUELLER, a citizen of the United States, residing at Chicago, in the county of Cook and State 5 of Illinois, have invented certain new and useful Improvements in Labeling-Machines, of which the following is a specification.

This invention relates to machines for applying labels to bottles, cans or other cylindrical containers, and its object is to provide a simple and highly efficient machine of this kind, which is rapid in operation, and which requires no attention except to supply the bottles or other containers to the 15 feeding device.

The invention also has for its object to provide a novel and improved label magazine having means for holding taut the labels as they are applied.

20 A further object of the invention is to provide a mechanism for applying labels to the necks of bottles, a label magazine being provided which is yieldingly supported to accommodate itself to different shaped bottle-necks.

25 Another object of the invention is to provide a feed table which is adjustable to different sized bottles.

With these objects in view, the invention 30 consists in a combination and arrangement of parts to be hereinafter described and claimed, reference being had to the accompanying drawings, in which—

Figure 1 is a front elevation of the machine; Fig. 2 is an end view thereof; Fig. 3 is a cross-section on the line 3—3 of Fig. 1; Fig. 4 is a horizontal section on the line 4—4 of Fig. 2; Fig. 5 is a vertical section of one of the label magazines; Fig. 6 is a 40 plan view of said magazine, and Fig. 7 is an enlarged elevation of the other label magazine.

Referring specifically to the drawings 9 denotes a hollow column of suitable height 45 supported on legs 10 rising from a base 11. This structure forms the supporting frame of the working parts of the machine. The column 9 is angular in cross-section and on one of its faces is rigidly mounted a plate 12 having an undercut vertical slideway in which is mounted a plate 13 carrying supports for the mechanism to be presently described. The plate 13 is vertically adjustable by a hand screw 14. The top of the

plate 13 has a horizontal outward extension 55 15 forming a table across which the bottles to be labeled are fed. By operating the hand screw, the table can be raised or lowered. One end of the table has an upward curve, as indicated at 16, to allow the bottles 60 rolling along the table to follow each other closely. Located a suitable distance above the top of the table are two endless bottle feeding belts 17 arranged side by side in spaced relation, and passing over pulleys 18 65 mounted on shafts 19 supported in suitable bearings carried by the column. The belts run in the direction of the length of the table and they carry the bottles from the end 16 to the opposite end of the table. One 70 of the shafts 19 has a drive pulley 20 which is belted to any suitable source of power. Mounted on top of and extending lengthwise of the table are two rubber strips 21 serving as cushions along which the bottles roll. 75 These cushions take up slight irregularities in the shape of the bottles.

In the table 15, near the entrance end 16 thereof, are two transverse slots 22 and 23, respectively, spaced in the direction of the 80 length of the table. Into each slot extends a roller 24 having its periphery projecting above the table top a sufficient distance to come in contact with the bottles as they roll along the same. The roller is supported 85 removably in bearings at the outer ends of angular arms 25 pivoted to the end walls of a trough 26, as indicated at 27. The other ends of the arms are weighted, as indicated at 28, whereby the roller is normally held up 90 in the slot of the table.

In each trough 26 is mounted a roller 29, the shaft of which is vertically slidable in slots 30 in the end walls of the trough. The shaft ends are supported by springs 31 in 95 the slots, whereby the roller is pressed upward into contact with the roller 24 above the same. The troughs are designed to hold a supply of liquid adhesive which is taken up by the rollers 29 and applied by the same 100 to the rollers 24, the latter, in turn, applying the adhesive to the sides of the bottles.

The troughs 26 are mounted on arms 32 connected at their inner ends and terminating thereat in a downturned portion 33 105 which is adjustably held by a set screw or other suitable clamping means 34, in a lug 35 extending outward from the plate 13.

The arms 32 extend transversely of the table, in view of which the troughs can be adjusted laterally of the table, and as the part 33 is vertically adjustable, the troughs 5 can also be vertically adjusted.

A lug 36 on the plate 13 carries a bracket arm 37 having a seat at its outer end to hold a vertical tube 38 which is angular in cross-section. The tube is secured in the 10 seat by a set screw 39. On the upper end of the tube is mounted a magazine 40 which holds a supply of labels to be applied to the bottles. In the bottom of the magazine, in line with the tube, is an opening through 15 which extends a rod 41, which latter is slidable in the tube and carries at its upper end a plunger 42 which works in the magazine. The labels are supported in a pile on top of the plunger and are fed to the mouth 20 of the magazine by the upward movement of the plunger. The plunger is carried upward by a weight 43 attached to one end of a line 44, the other end of which is connected to the stem 41, the tube having a slot 25 45 through which the latter connection passes. Intermediate its ends the line is trained over a pulley 46 which changes the direction thereof. The magazine is open at the top, and the latter is flush with the top 30 of the table 15 and seats in an opening therein. At the top of the magazine are three short fingers 47 which engage the uppermost one of the labels, in the magazine, for a purpose to be presently described.

The mechanism thus far described affixes 35 labels to the sides of the bottles, and its operation may be summarized as follows: The bottles are fed to the end 16 of the table 15 and upon rolling down the incline, they 40 are propelled forward by a rolling motion toward the opposite end of the table by the belts 17. The rollers 29 are given a slow rotary motion through a drive pulley 48 whereby the adhesive in the troughs 26 is 45 fed to the applying rollers 24 by the rollers 29. As the bottles roll across the rollers 24 a coating of adhesive is applied, and the rollers being spaced, it will be seen that the coating is applied to two places on each 50 bottle. The rollers work between the strips 21, and the latter hold the bottles out of contact with the table so that the adhesive applied by the rollers may not be rubbed off. When the bottle passes the open top or 55 mouth of the magazine 40, the same being filled with labels, urged upward by the plunger 42, the coated parts pick up the top label, and as the bottle continues to roll forward the label wraps around the bottle. 60 The magazine is so spaced from the adhesive applying rollers 24 that the glue marks register with the label as the bottle comes above the magazine. The fingers 47 are very small and serve as retainers for the label, 65 the forward finger being set slightly lower

than the two side ones so as to more tightly hold the label. This forward finger tends to hold the label taut while it is wrapping around the bottle, the side fingers however readily releasing the corresponding edges 70 of the label. The belts 17 also serve to press the label on the bottle. The glue marks are spaced a trifle less than the width of the label in order that the glue may not spread out from beneath the label when pressure is 75 brought to bear on the latter by the belts 17.

One side of the magazine 40 is hinged at the bottom, as indicated at 49, to permit the ready insertion of the labels. On top of the table 15 is also mounted a guard rail 50 80 against which the base of the bottles abut.

A mechanism for applying labels to the bottle-necks is also provided, which mechanism will now be described: An adhesive applying belt 51 passes over pulleys 52 85 mounted loosely on shafts 53 which are hinged at 54 to the outer edge of the table 15 in order that the belt may accommodate itself to any unevenness of the bottle-necks or different shapes. The adhesive is applied 90 to the outer surface of the belt by a roller 55 in contact therewith, said roller being mounted in a supply-trough 56 carried by one of the arms 32 alongside one of the troughs 26. As the labels completely encircle the bottle-necks, the adhesive applied by the belt 51 extends entirely around the necks. The label magazine 57 is hinged at 95 58 to an arm 59 which latter, in turn, is hinged to the table 15, as indicated at 60. 100 The arm has an upstanding lug 61 carrying a set screw 62 which is opposite the edge of the table and serves to limit the upward swing of the arm. The outer end of the arm to which the magazine is hinged has a down-turned portion 63 carrying a set screw 64 which is adapted to engage the side of the magazine. From the table extends an arm 65 to which is anchored the upper end of a 105 coiled spring 66, the lower end of which 110 latter is connected to the side of the magazine, as indicated at 67.

By mounting the magazine 57 as hereinbefore described, it is free to adapt itself to different shaped bottle-necks. 115

Except, as noted, the magazine 57 and the parts associated therewith are the same as the magazine 40 and its associate parts. The operation is also the same, the labels being 120 wrapped around the bottle-necks as they pass the open top of the magazine.

By means of the screw 14 the table 15 may be raised or lowered with respect to the feed belt 17, to accommodate the machine to different sized bottles. 125

I claim:

1. In a label-applying machine, an endless adhesive applying belt, pulleys over which the belt travels, hinged shafts supporting the pulleys, a label magazine to the rear of 13

the belt, and means for feeding the objects to be labeled along the belt and across the mouth of the magazine.

2. In a label-applying machine, a label magazine which is hinged to adapt itself to different shaped objects to be labeled, and means for feeding such objects across the mouth of the magazine.

3. In a label-applying machine, a label magazine, a support, a pivoted arm carried by the support, a label magazine hinged to the outer end of the arm, said end of the arm being downturned, a set screw carried by said downturned end of the arm and engageable with the side of the magazine, an upstanding lug on the arm, a set screw carried by the lug and engageable with the support, and a resilient connection between the support and the magazine.

4. In a label-applying machine, a support, a feed-table carried by the support and having openings, an arm carried by the support and extending transversely beneath the table, an adhesive container adjustably mount-

ed on the arm, an adhesive-applying roller mounted in one of the table openings, a feed-roller in the container and in contact with the applying roller, and a label magazine mounted in another table opening to the rear of the adhesive applying roller.

5. In a label-applying machine, a support, a feed-table carried by the support and having openings, a vertically adjustable arm carried by the support and extending transversely beneath the table, an adhesive container adjustably mounted on the arm, an adhesive-applying roller mounted in one of the table openings, a feed-roller in the container and in contact with the applying roller, and a label magazine mounted in another table opening to the rear of the adhesive applying roller.

In testimony whereof I affix my signature in presence of two witnesses.

MAX M. MUELLER.
